GAS BURNER

Frank J. Sabo, Walkerton, Ind., assignor to Arrowhead
Engineering Corporation, Walkerton, Ind., a corpora-
tion of Indiana

Filed Jan. 30, 1961, Ser. No. 63,750

Term of patent 14 years

(Cl. D81—10)

FIG. 3

FIG. 4

FIG. 5

FIGURE 1 is a top plan view of a gas burner, showing my new design;

FIGURE 2 is a side elevational view;

FIGURE 3 is a bottom view thereof;

FIGURE 4 is an end elevational view taken from the left of FIGURE 1; and

FIGURE 5 is an end elevational view taken from the right of FIGURE 1.

I claim:
The ornamental design for a gas burner, substantially as shown.
